US00D777762S

(12) **United States Design Patent** (10) **Patent No.:** **US D777,762 S**
Park et al. (45) **Date of Patent:** **** Jan. 31, 2017**

(54) **DISPLAY SCREEN OR PORTION THEREOF
WITH GRAPHICAL USER INTERFACE**

(71) Applicant: **Samsung Electronics Co., Ltd.,**
Suwon-si, Gyeonggi-do (KR)

(72) Inventors: **Yongman Park**, Yongin-si (KR);
Soyoung Lee, Seoul (KR); **Jakyung Lee**, Seoul (KR)

(73) Assignee: **SAMSUNG ELECTRONICS CO., LTD.**, Gyeonggi-Do (KR)

(**) Term: **15 Years**

(21) Appl. No.: **29/548,762**

(22) Filed: **Dec. 16, 2015**

(30) **Foreign Application Priority Data**

Sep. 14, 2015 (KR) 30-2015-0046768

(51) **LOC (10) Cl.** **14-04**

(52) **U.S. Cl.**

USPC **D14/486**

(58) **Field of Classification Search**

USPC D14/485-95; D18/24-33; D19/6, 52;
D20/11; D21/324-33; 715/700-867,
715/973-77

CPC G06F 3/048-3/0489

(57)

CLAIM

The ornamental design for a display screen or portion thereof with graphical user interface, as shown and described.

DESCRIPTION

The sole FIGURE is a front view a display screen or portion thereof with graphical user interface showing our new design.

The broken line showing of the alphanumeric characters, symbols, graphic elements and the display screen or portion thereof forms no part of the claimed design.

1 Claim, 1 Drawing Sheet
